UNITED STATES PATENT OFFICE.

ERNEST GAUTHIER, OF CHICAGO, ILLINOIS, ASSIGNOR TO WESTERN ELECTRIC COMPANY, INCORPORATED, OF NEW YORK, N. Y., A CORPORATION OF NEW YORK.

PRESS.

Application filed December 27, 1922. Serial No. 609,332.

This invention relates to presses, and more particularly to presses of the type having a crankshaft and reciprocating plunger or slide.

5 The primary object of the invention is to provide a press of the type having a crank-shaft and a reciprocating slide with means for indicating the amount of pressure exerted thereby in the performance of a given 10 operation in punching, stamping or drawing, or otherwise working on parts made of metal or other materials.

A still further object is to provide, in a press, a novel and improved arrangement of 15 extremely simple design, whereby suitable pressure indicating devices may be attached to, and operated by the press itself, during the performance of its ordinary duties.

With these and other objects in view, as 20 will more fully appear as the description proceeds, this invention furthermore consists in certain novel and improved constructions and arrangements of parts, as will hereafter be fully described and particularly 25 pointed out in the appended claims.

The determination of the amount of pressure required to perform a given piece of work by means of a punching or stamping press is a matter of considerable importance, 30 and in certain cases of extreme importance to the manufacturer and to the designer. The field of this class of machinery, however, is so vast, and its range of operations so diversified, that it is practically impossible to determine this factor by calculation, 35 except in a minority of instances. The elements to be considered in an accurate calculation are furthermore so many, and often so apt to have to be estimated with only a 40 distant approximation, and the calculations themselves, while producing results which are often unreliable, require so much time and care, that in general the rule of thumb is applied in current practice, and the guidance of calculations prior to determining 45 the thickness and structure of the metal to be used, the press to be employed, and the type of tools best suited for the work, utterly neglected.

50 The results of this blind method of procedure are, of course, detrimental to production, inasmuch as in some cases a machine

too small for the work may be employed, and in a larger number of cases a too large one may be utilized which might be more 55 efficiently used in heavier duties.

It is obvious that a means for permitting a rapid and reliable determination of the amount of pressure required to perform a given operation, greatly simplifies the problems connected with the use of presses generally, enabling the operator to distribute the work to his different machines according to their various capacities, with complete elimination of uncertainty and guess-work, 60 and enabling the operator to adjust his machines to the pressure required, when means of pressure adjustment are provided.

Press work of all descriptions is always 70 produced by means of tools comprising a die, or female member, and a punch, or male member, the punch being generally carried by the plunger or slide, which is the movable part of the machine, while the die is mounted on the bed plate or stationary part. 75

The plunger is capable of reciprocating motion, moving the punch towards and away from the die, and the pressure necessary to perform the work is, of course, exerted by the punch against the die and is transmitted by each member to the respective holders. In some types of presses, both members are caused to move simultaneously against or away from each other, while in other types of machines closely allied thereto, like for instance wire forming machines, various tools may be operated simultaneously or in succession, by a plurality of holders or slides.

No matter what type of control is used, 90 however, an elementary press operation always resides in the combined action of the two members of which the tool is composed on the material out of which the work is produced; and said operation invariably 95 takes place through the exertion of pressure by one member against the other, or by both members against each other. In stamping and forming operations, said pressure must be sufficient for the material to acquire a given form or imprint, such as determined by the design of the punch and die, and in punching and shearing and blanking operations, said pressure must be sufficient for the 100

material to be sheared or cut according to a predetermined outline also controlled by the tools used.

My improved means of determining the amount of pressure thus required consists essentially in interposing suitable means between one of the tool holders and the other parts of the machine to which the pressure of the same is transmitted, capable of operating pressure indicating means which may be connected thereto, so that an indication is obtained directly through an actual performance of the operation of the press. The construction of this mechanism is of such a nature as not to interfere with the normal operation of the tool holder and of the tool member connected thereto, and entails but slight changes in the design of the press itself. With the use of this mechanism the pressure developed in the performance of the work will be transmitted by the tool holder through the medium of said interposed means, which will at the same time cause the operation of the pressure indicating means. A direct and exact reading may thus be obtained in each case, giving an immediate and reliable basis on which to regulate the work.

In practice, the device may be applied to one press which serves as a master press. A given piece of work is performed by the master press, and the amount of pressure necessary in the operation noted. The work is then distributed to the presses in the department which are best suited therefor, or else the presses are adjusted in accordance with the pressure required.

Such a means of determining the pressure necessary to perform any given piece of work is also open to extensive application in testing punches and dies and also the physical properties of various materials, and in making comparative tests of pressures required by different thicknesses of the same material.

The scope of my invention is not to be limited by the nature of the medium selected in order to carry the same into practice, or by the details of the mechanical arrangements adopted, or by the nature of the indicating means used. It is well known that pressure indicating gauges of various descriptions may be operated by the action of a spring, or by the action of a fluid, or by the action of some other suitable agent, and the selection of a proper medium and of a suitable working arrangement thereof, will be subject to considerations of conditions affecting various cases.

In the accompanying drawing which illustrates one embodiment of the invention,

Fig. 1 is a front view in elevation of the upper part of a press to which said embodiment of the invention has been applied; and, Fig. 2 is a fragmentary detail front view

in elevation, partly sectioned, and on a larger scale, illustrating the manner in which the invention is carried into practice in the arrangement shown in Fig. 1.

In the machine shown in the drawings, which is of a well known type where the plunger or slide is attached to its connection by means of a ball and socket joint, my invention is applied by inserting the pressure gauge operating medium between the plunger and its connection, and more particularly, by providing a fluid cushion between said two parts.

Referring to the drawings in detail, designates the body of the machine 10, the stationary bed plate thereof, 11 its crank-shaft carrying a flywheel 12, 13 the adjustable connection between said crankshaft and the plunger or slide 14, and 15 the ball end of said connection.

The attachment between the ball end 15 of the connection and the plunger, is effected by means of an adjustable socket constituted of two parts 16, 17, which are machined to form a spherical cavity with an opening 18 at the top, within which ball 15 is received. Said two parts are normally lodged within a chamber or receptacle 19 provided within the plunger, and are maintained in position by means of a nut 20, secured by a check nut 21. The relative adjustment of said nut and check nut, furthermore permits a very minute adjustment of the pressure with which ball 15 is maintained between parts 16, 17.

A pressure gauge 22, of any suitable type is connected by means of a flexible hose 23, or other suitable medium, to a tubular opening 24 made through the wall of the plunger, leading from the exterior to the lower part of chamber 19. A small quantity of liquid 25 is introduced within said chamber, and the position of socket parts 16, 17, adjusted accordingly by means of nut 20 and check nut 21, so that there will be no play between the lower part 16 and the liquid cushion thus formed.

Upon the plunger being made to descend to perform a given piece of work, the pressure developed will be exerted between the plunger and part 17 through the medium of fluid 25; which under said pressure will cause corresponding indications to appear on the dial of the gauge 22 connected thereto.

Said gauge may be of any suitable type, registering, or non registering, although it may be easier to detect the maximum pressure reached, if the gauge is provided with means for registering the same.

A washer 26 secured to the plunger part 17 prevents the fluid 25 from leaking past the plunger.

It is to be understood that the nature of the gauge operating medium may be different from that shown, and that its location

is not limited to the one shown in the drawings; but may be disposed in any position where it might be subjected to the pressure developed during the performance of the work.

The chief advantage achieved by the mechanism above described, is of course the elimination of guess work in the operation of presses, and the ease with which reliable and definite data may be obtained in a practically unlimited variety of cases; and its chief feature is that the data thus procured are obtained directly through the performance of the individual operations themselves, in the ordinary manner.

The improved mechanism above described, however, is open, as stated above, to an endless variety of applications less directly related to specific manufacturing problems, although quite as important; providing, as it does, means of an absolutely reliable nature, and of easy application, whereby some physical properties of various materials may be determined, which entailed heretofore the employment of lengthy and costly methods, producing less dependable results.

What is claimed is:

1. The combination with a press having a crankshaft and reciprocating slide, means connecting said crankshaft and slide, of a pressure indicating means, and means interposed in said connecting means and controlling the operation of said pressure indicating means.

2. The combination with a press having a crankshaft and a reciprocating element actuated thereby, of pressure indicating means, a body of fluid deformable by an operation of said reciprocating element, and means connecting said fluid with the pressure indicating means.

3. The combination with a press having a crankshaft, a tool holder, and a member connecting said tool holder to said crankshaft, of a pressure gauge, and means interposed between said tool holder and said connecting member controlling the operation of said gauge.

4. The combination with a press having a crankshaft, a tool holder having a cavity, and a member connecting said tool holder to said crankshaft, of a pressure gauge, and a body of liquid disposed in said cavity and connected to said gauge, said liquid interposed between said tool holder and said connecting member and controlling the operation of said gauge.

5. The combination with a press having a crankshaft, a tool holder provided with a cavity, a member adjustable therein, a connection between said member and said crankshaft, permitting motion of said tool holder relative to said member in a direction opposite to that of the working stroke, of a pressure gauge, and a body of liquid filling the space in said cavity between said member, and said tool holder connected to and operating said gauge.

6. The combination with a press having a crankshaft, a tool holder provided with a cavity, a ball socket movable therein, means for adjusting and retaining said ball socket in position, a member provided with a ball-shaped end connecting said ball socket to said crankshaft, of a pressure gauge, and a body of liquid connected thereto filling the space in said cavity between said ball socket and said tool holder.

7. The combination with a press having a crankshaft and plunger actuated thereby of a pressure gauge, and a body of liquid contained within said plunger adapted to be subjected to the pressure exerted thereby, and a flexible connection between said body of liquid and said pressure gauge.

8. The combination with a power actuated press having an actuating element, a tool holder and a member connecting said tool holder to said actuating element, of a pressure gauge and means interposed between said tool holder and said connecting member controlling the operation of said gauge.

In witness whereof, I hereunto subscribe my name this 27 day of November A. D., 1922.

ERNEST GAUTHIER.
